UNITED STATES PATENT OFFICE.

ROGER S. LITTLEFIELD, OF EMPIRE CITY, OREGON.

METHOD OF BUILDING JETTIES.

SPECIFICATION forming part of Letters Patent No. 324,857, dated August 25, 1885.

Application filed December 26, 1884. (No model.)

To all whom it may concern:

Be it known that I, ROGER S. LITTLEFIELD, a citizen of the United States, residing at Empire City, in the county of Coos and State of Oregon, have invented certain new and useful 5 Improvements in Method of Building Jetties or Breakwaters, of which the following is a description.

My invention relates to a new method of 10 building or constructing jetties or breakwaters; and it consists in the following steps of construction: first, starting a track at the point where the jetty is to begin, upon which dumping-cars and a pile-driver may be run; 15 second, dumping the material or filling until the "rise" reaches a required level above or below water-surface; third, driving piles into the slope of the dump on which the track may be extended.

20 Hitherto in the building of jetties great expense has been incurred by the use of very long piles. The piles have been driven into the sea-bottom from a scow, a track then laid on them, and the broken stone or other filling dumped in around them from cars on the tramway above. Under this method work was 25 greatly delayed, especially in stormy weather, by the force of the heavy seas breaking off the piles, thus weakening the tramway. My 30 method obviates these delays, inasmuch as the filling and the piles are placed at practically the same time, one thus supporting the other. My method also requires short piles, as they are driven into the slope of the forward end

of the jetty and are supported by it. No advantage attains in driving a pile beyond the point of its breakage. In other words, the point to be aimed at is to have the pile break off before it will pull or give under a strain, and a pile driven into the dump or end of a jetty 40 made of loose stone, or same intermixed with mattress-work, will be properly supported to fulfill this requisite.

In the drawings, Figure 1 represents a longitudinal section of a jetty in course of construction, with a dumping-car filling in around the piles. Fig. 2 is the same with a pile-driver at work in the place of the car.

A represents the jetty, into the forward end or dump *a* of which are driven piles *B* by means of any pile-driver, as *C*. After a sufficient number of piles have been driven the track on the top of the jetty is extended upon them and the dumping-car *D* run on to fill in around them.

55 I claim—

The herein-described method of constructing breakwaters and jetties, which consists in beginning a fill at the point where the jetty is to be constructed, driving piles into the slope 60 of said fill, extending a track on the piles, then filling about said piles, and so continuing in order until the jetty is completed.

ROGER S. LITTLEFIELD.
